BARREL HOOP

Clarence C. Stuewe, Cleveland, Ohio, assignor to
 The Greif Bros. Cooperage Corporation, Cleve-
 land, Ohio, a corporation of Delaware

Application April 28, 1948, Serial No. 23,672

7 Claims. (Cl. 217—89)

1 This invention relates to improvements in barrels, kegs, or the like, and more particularly to an improved end hoop therefor.

As is well known to those versed in the art, it is common practice to make barrels or kegs which comprise a body made of staves that are held in position by hoops. The ends of the barrels are closed by heads which are engaged in a groove running around the interior of the barrel, spaced from the end known as the croze, the head being held in place by an end hoop which engages the exterior of the staves and holds them inward with the edge of the head seated in the croze. The hoop is held in place by nails or staples which are driven through the staves and usually penetrate the edge of the head.

The assembly of the head on the barrel is accompanied with some difficulty, usually requiring the services of one having a particular skill in effecting the same.

The hoop is usually a closed band of steel which is of smaller diameter at one end than the other, the same being shaped to conform to the slant of the barrel wall which tapers from the bilge to the end.

When once assembled, the edge of the staves may extend unprotected beyond the hoop, and, in any event, the inner surface of the ends of the staves, known as the chime, is without protection. Since the barrels are customarily stored on their ends, there is a tendency for the chimes and ends to accumulate dirt and to become mutilated.

Not only is it difficult to effect the closure, but it is also difficult to open the barrel. The nails, or staples, may be withdrawn and the hoop removed, but this allows the staves to spring apart and often results in a loss of contents. It is customary to knock the head of the barrel in to obtain access to its contents. This results in the head being splintered and often falling into and contaminating the contents of the barrel. Barrels opened in this manner are usually so mutilated as to make their reuse impractical.

By my present invention, I am able to make a closure for a barrel which enables the same to be used by persons without particular experience or skill. The hoop is such that the barrel staves are pulled gently but firmly into close fitting engagement with each other. The invention also prevents the head from falling into the barrel during assembly. After assembly, the hoop not only holds the head and the staves in position but so cooperates with the staves and head as to securely hold itself in position without the need of nails or staples. Since no nails or staples are

used, the staves and the head are never split. The hoop protects the edges of the staves, preventing moisture from entering the porous ends, guarding them against damage and preventing them from being damaged. Any dirt or extraneous matter which accumulates on the hoop may be easily wiped off.

When it is desired to open the barrel, the hoop may be loosened sufficiently to allow the head to be easily lifted from position, but the structure is such that it still retains engagement with the staves and does not allow them to spring apart, with the resultant loss of contents. Furthermore, the hoop is so designed that the head will not ordinarily accidentally fall into the barrel when it is loosened but may be removed without contaminating its contents.

With ordinary use, the barrel may be reused over and over again and still remain in a tight and satisfactory condition. Furthermore, the hoop of my invention is such that it is usable with conventional barrels and heads.

Still other advantages of the invention, and the invention itself, will become more apparent from the following description of an embodiment thereof which is illustrated by the accompanying drawings and forms a part of this specification.

In the drawings:

Fig. 1 is a fragmentary perspective view of the upper end of a barrel with the hoop of my invention in place;

Fig. 2 is a fragmentary enlarged view taken through the edge of a barrel and showing in section the manner in which the hoop of my invention cooperates with the staves and head; and

Fig. 3 is an enlarged fragmentary elevational view showing a form of securing device for the hoop and showing in dotted line certain features which would otherwise be hidden.

As best shown in Fig. 1, the barrel may be of conventional form and comprise the usual staves 10 which are held in position by hoops such as 11 which may be conventional. The staves taper from the bilge 12 toward the end in a manner well known.

The head is illustrated as being formed in sections 13, the edges being formed wedge shaped as shown at 14, Fig. 2, adapted for engagement in the croze 15 which is disposed around the inner ends of the staves spaced from the ends by the slanting surface 16 called the chime. The structure so far described is conventional and is common practice to those versed in the cooperage art.

The hoop of my invention comprises a split channelled band, having a croze seat and held in

place by expandible and contractible means which bridges the ends.

As best shown in the figures, it comprises a channeled member which is split at 20 and includes an outer skirt 21 shaped to conform to the outer surface of the barrel staves. It is provided with a bight 22 which extends over the ends of the staves 10. It then extends downward at 23 over the chime 16 and is provided with a V-shaped croze seat 24. The croze seat conforms closely to the contour of the croze.

Below the croze seat 24, an inwardly extending flange 26 is provided, this flange extending continuously with the hoop around the inside barrel except for the split.

Secured to the hoop spaced from the ends are a pair of bosses 27 and 28 having bores 27'—28'. A bolt 29, having a head 30, extends through the bores in the bosses with the head engaging one end of the boss 27. The other end of the bolt is threaded at 31 for the reception of a nut 32, which nut engages the outer end of the boss 28.

In operation, the bolt may be of sufficient length so that, with the same in place, the ends 20 of the hoop may be spread apart sufficiently that the wider, lower, open edge of the channel may be readily slipped over the free edges of the staves, the croze seat 24 snapping into the croze on the staves.

The head may then be set on the flange 26, where it is supported prior to tightening of the hoop. Next, all that need be done is to tighten the bolt 29, which may be done with a screw driver or a wrench.

It will be noted that the assembly consists of but a few simple consecutive operations and that there is not the difficulty of holding the head in place while the hoop is being applied. The operations may be performed without hammering and the danger of splintering the wood, which splinters might fall into the container.

It will be noted that the bolt and its connection to the bosses on the ends of the hoop causes the skirt 21 to be contracted, which contraction is transmitted to the exterior of the barrel staves. This causes the staves to be pulled inward and tightly together.

The croze 15 and the croze seat portions 24 of the hoop are then pushed inward against the edge of the head which causes the head to seat securely in the croze seat. The hoop being made of metal, the wooden parts, if displaced by compression, merely follow the contour of the metal which thus causes a more effective seal. The hoop, not being of fixed diameter, as ordinary hoops, can thus be contracted tighter, and the greatest force is centered at the point or along the line where the greatest force is needed, namely, in a line passing through the apex of the croze into the barrel head. Therefore, there is no undue force placed on the rim of the barrel at the chime, although this portion is also forced inwardly securely but not sufficient to cause a strain which might otherwise result in breakage of the chime above the croze.

It will thus be seen that protection is afforded for the edge of the barrel and the chime; that the seating of the parts is such that all the cracks are closed, preventing outward seepage of the contents or inward seepage of water, dirt or other foreign material.

Preferably, the hoop is made of such a length that when the ends are brought into abutting relation, the desired seating of the parts is effected. As shown in Fig. 3, however, it may be desirable

to have a portion 40 shown in dotted lines which is sized somewhat smaller than the other end of the hoop and is adapted to extend under the other end in telescoping relation. This part would not necessarily have the croze seat on the flange thereon.

It will further be noted that there are no nails or staples needed to hold the hoop in place, and that because of the interlocking engagement of the parts, they are held more securely in place than staples or nails would be, and cannot be removed accidentally without loosening the bolt.

The usual bead that is provided on hoops may also be omitted, thus providing a more smooth exterior surface which cannot as readily be caught on extraneous objects.

This structure also facilitates the shipping of empty barrels because the head is quickly and easily assembled and removed. The barrels may have the heads in place even when empty, which prevents contamination of the inside of the barrel.

When it is desired to remove the head, the bolt need merely be loosened; the hoop expands and the parts become loose enough so that the head again rests on the flange 26. The head may then be lifted off the flange without the use of special tools and without breakage.

Although I have shown a preferred and simple form of fastening means for the ends of the hoop, it will be appreciated that many other forms other than that shown may be used without departing from the spirit or scope of the invention.

Furthermore, the placement of the bosses which receive the bolt, although preferably opposite the croze seat can be varied and they may be raised or lowered from the position without materially affecting the invention in its broader aspects.

Having thus described my invention, I am aware that numerous and extensive departures may be made therefrom without departing from the spirit or scope of the invention as defined in the appended claims.

I claim:

1. In combination with a barrel or keg having staves with a croze provided adjacent the ends thereof and a head for engagement in the croze, an end hoop for said barrel comprising a metallic member extending around the outside of the barrel, over the end of the barrel staves and across the chime and formed with a croze lining portion and a flange below said portion extending inwardly, said hoop being divided transversely and means secured to the hoop adjacent the ends for loosening and tightening the hoop, a barrel head disposed with its edges resting on said flange and adapted to be engaged with the croze engaging portion of said hoop.

2. In combination with a barrel or keg having staves forming the side of the barrel, the inner ends of said staves being formed with a croze and a chime, a hoop formed with a skirt surrounding the staves around the end of the barrel and being turned over the edge of the barrel and extending downward inside of the staves to cover the chime and having a portion contoured like and adapted to engage in said croze below the chime and a flange extending inwardly toward the axis of the barrel below the croze engaging portion, said hoop being formed with separable ends, and means secured to the hoop adjacent the ends for contracting and expanding said hoop on the barrel.

3. In combination with a barrel or keg having

staves forming the side of the barrel, the inner ends of said staves being formed with a croze and a chime, a hoop formed with a skirt surrounding the staves around the end of the barrel and being turned over the edge of the barrel and extending downward inside of the staves to cover the chime and having a portion contoured like and adapted to engage in said croze below the chime and a flange extending inwardly toward the axis of the barrel below the croze engaging portion, said hoop being formed with separable ends and having end portions for overlapping sliding engagement and means secured to the hoop adjacent the ends below the edge of the barrel and outside thereof for contracting and expanding said hoop on the barrel.

4. In combination with a barrel or keg having staves forming the side of the barrel, the inner ends of said staves being formed with a croze and a chime, a hoop formed with a skirt surrounding the staves around the end of the barrel and being turned over the edge of the barrel and extending downward inside of the staves to cover the chime and having a portion contoured like and adapted to engage in said croze below the chime and a flange extending inwardly toward the axis of the barrel below the croze engaging portion, said hoop being formed with separable ends, and means secured to the hoop adjacent the ends for contracting and expanding the said hoop on the barrel, a head for said barrel supported on said flange when the hoop is expanded, and means to contract said hoop for engaging the staves and pulling them tightly together and said head having a croze engaging portion engaged with the croze portion of the hoop to seal the barrel when the hoop is contracted.

5. In combination with a barrel having a side portion and being formed with a groove extending around the inner periphery adjacent the end, a hoop compressing a channeled member formed to extend over the edge of the barrel and extending from the edge toward the center of the barrel for a distance on each side of the edge, the inner portion of said hoop being formed with a V-shaped portion for engagement in said groove, a head for said barrel having an edge formed for engagement with said V-shaped portion, said hoop being divided to provide movable ends and means in engagement with said ends to expand and contract the same.

6. In combination with a barrel having a side portion and being formed with a groove extending around the inner periphery adjacent the end, a hoop compressing a channeled member formed

to extend over the edge of the barrel and extending from the edge toward the center of the barrel for a distance on each side of the edge, the inner portion of said hoop being formed with a V-shaped portion for engagement in said groove and a flange disposed below said V-shaped portion and extending inwardly, a head for said barrel having an edge formed for engagement with said V-shaped portion, said hoop being divided to provide movable ends and means in engagement with said ends to expand and contract the same, said hoop formed to pull the end of the barrel into tight engagement with said head with the V-shaped part between the head and groove and said flange disposed for supporting engagement with the head at all times.

7. In combination with a barrel or keg having staves forming the side of the barrel, the inner ends of said staves being formed with a croze and a chime, a hoop formed with a skirt surrounding the staves around the end of the barrel and being turned over the edge of the barrel and extending downward inside of the staves to cover the chime and having a portion contoured like and adapted to engage in said croze below the chime and a flange extending inwardly toward the axis of the barrel below the croze engaging portion, said hoop being formed with separable ends, and means secured to the hoop adjacent the ends for contracting and expanding the said hoop on the barrel, a head for said barrel supported on said flange when the hoop is expanded, and means on the exterior of said hoop opposite to said croze engaging portion to contract said hoop for engaging the staves and pulling them tightly together and said head having a croze engaging portion engaged with the croze portion of the hoop to seal the barrel when the hoop is contracted.
